ELECTRICAL RESISTANCE DEVICE

Leo G. Downing and James V. Kindall, Riverside, Calif.,
assignors to Bourns, Inc.

Filed July 14, 1965, Ser. No. 472,002

7 Claims. (Cl. 338—20)

The invention herein described pertains to electrical resistance devices and more particularly to improvements in that class of resistance devices constructed and arranged to provide an output that is exponentially related to the input potential or applied voltage.

There are on the market voltage-variable electrical resistance devices, known as varistors, which are characterized by a negative temperature coefficient of resistance. It is known in the art to assemble a plurality of varistors in series relationship, as by stacking a plurality of the disc-like devices in a cylindrical container with a corrective or compensating network in series, to provide an impedance unit characterized by an output potential that is functionally related to an input potential by other than a linear relationship, such as, for example an exponential relationship. Thus by judicious selection of varistors, a desired functional relationship, such as the cosine, or the sine, or mathematical square, may be attained. Means and modes for attaining such results are, for example, set out in U.S. Letters Patent No. 3,211,901, issued Oct. 12, 1965, the disclosure of which is incorporated herein by reference, to any extent necessary to a complete understanding of the present invention.

In the prior are exponential "resistors" or resistance devices hereinabove referred to, the polycrystalline semiconductive materials, formed as disc-like tablets of selected material such as carbide crystals compacted into a unitary mass and bearing a solder-coated flashing of copper on the faces, were disposed in a cylindrical housing under some compression so as to maintain them in series relationship. As so constructed and arranged, very slight movements of the discs relative to each other and relative to the terminal discs occurred incident to changes of temperature and incident to the resistor being vibrated in use. Such movements naturally changed the disc-to-disc contact resistance, and thus was the cause of electrical "noise" in the circuit containing the resistor and also was the cause of gross variations of the terminal-to-terminal resistance.

The present invention overcomes the aforementioned objectionable characteristics or features of the prior art nonlinear impedance units, and provides a unit comprising a series or group of polycrystalline semiconductive devices such as varistors electrically in series arrangement, in which no appreciable change in the disc-to-disc resistance occurs irrespective of repetitive changes in temperature over a wide range and irrespective of severe vibration. According to the invention, the disc-like semiconductive units (such as varistors) are selected as may be required to attain the desired variation of resistance with variation of applied potential, and are assembled into a stack, in axial alignment, with a small drop of highly conductive, highly adhesive self-curing conductive cement between each unit and that next adjacent thereto. Thereafter, the disc-like units are maintained in pressed-together relationship in axial alignment, as by being held in a cylinder, during curing (hardening) of the applied cement. Thus a unitary mass, comprising a series of series-connected nonlinear resistors, is produced. The resulting integral unit is characterized by substantially zero electrical resistance between contacting faces of any pair of the stacked devices due to the highly conductive cement; and is further characterized by extreme constancy of the inter-resistor or face-to-face contact re-

2

sistance during heat or temperature cycling and during application of vibratory stresses. As will be evident, the areal extent of interface contact between two of the disc-like resistive devices is very large relative to the overall size and/or mass of one of the devices, whereby the forces of the adhesive bond are very large as compared with any externally applied opposing force, and the bonds are thus highly effective in maintaining the devices in fixed electrical and mechanical relationship in the integral group. As may be expedient and desirable, the integrated stack of semiconductive resistive devices may be housed in a closely fitting insulated tube in which may also be enclosed the fixed-value resistors, compensating means, terminal devices and insulators, all as hereinafter described in greater detail.

The preceding brief general description of the invention makes it evident that a principal object of the invention is to provide improvements in nonlinear voltage-variable resistor units.

Another object is to provide an integrated resistor unit comprising a plurality of voltage variable resistors, which unit is characterized by electrical immunity to extreme vibration and heat-cycling.

Another object of the invention is to provide an integral unit comprising a stack of face-to-face varistors, the unit being characterized by freedom from face-to-face electrical contact noise.

Another object of the invention is to provide a stack of disc-like polycrystalline semiconductive resistors which are both mechanically bonded together to form an integral unit and electrically interconnected in series by a solid electrically conductive medium.

Other objects and advantages of the invention are hereinafter stated or made evident in the appended claims and following description of a preferred form of structure according to the invention, reference being made in the description to the appended drawings forming a part of this specification.

In the drawings:

FIGURE 1 is a pictorial view, to no particular scale, of a voltage-variable nonlinear resistive device incorporating an integrated unit of electrical resistors, according to the invention;

FIGURE 2 is a longitudinal cross-sectional view of the device depicted in FIGURE 1 but to larger scale, with incidental structures not sectioned;

FIGURE 3 is a pictorial view, to an arbitrary scale, showing a single varistor device of the general character of those used in a structure according to the invention, with a part cut away;

FIGURE 4 is a sectional view of structure comprised in the resistive device depicted in FIGURE 1, the section being taken as indicated by broken line and arrows at 4—4 in FIGURE 2; and

FIGURE 5 is a view similar to FIGURE 4 but taken as indicated at broken line 5—5 in FIGURE 2.

Referring now to the drawings and to FIGURE 1 in particular, the resistive device is denoted generally by ordinal 10. It comprises a cylindrical shell 12, end closures 14 and 16 (FIGURE 2) and terminal wires or "pigtails" 18 and 20, with other components enclosed in the housing formed by the shell and end closures.

As depicted in FIGURE 2, the device includes among other components disposed within shell 12, a stack of exemplary disc-like polycrystalline semiconductive resistive devices which in this case are chosen to be silicon carbide varistors denoted by ordinal 22. As indicated in FIGURE 3, each varistor comprises a round flat-faced disc of shape-retaining resistive silicon carbide crystals compacted with a binder of, for example, thermosetting synthetic resin. The varistor comprises at each face

thereof a very thin layer or "flash" of copper 22c which may cover all of the face or as shown only a major part of such face; and overlying at least some of the copper at each face a respective coating of solder or tin 22s. Thus the individual varistor has a body and two terminals, the latter being constituted by the applied copper and tin. The terminals of next-adjacent varistors in a stack are thus arranged and of a nature favorable for effecting a good series electrical interconnection of the contacting varistors. In the illustrations the thicknesses of the applied flashing and tin or solder are grossly exaggerated, for convenience of illustration. In practice the applied materials are very thin.

According to the invention and as best illustrated in FIGURE 2, a stack of the polycrystalline semiconductive resistors 22 is assembled in coaxial arrangement, with a drop of conductive hardenable adhesive 24 between each pair of abutting resistor terminals. As the resistors are pressed together in the stack the adhesive spreads and in each case covers substantially all of the tin or solder 22s and preferably also at least some of the copper 22c, to form a film-like layer bonding the resistors together. The adhesive film is depicted in FIGURE 2 grossly enlarged in thickness for convenience of illustration, it being understood that the film is such as to permit the abutting solder layers to come into contact at a plurality of points or areas but elsewhere filling the interface voids and adhesively binding the resistor discs together into a unitary mass. The adhesive, formed preferably of silver flake and thermosetting resin, is permitted to cure at room temperature while the assembled stack of resistors is maintained in a cylindrical array under moderate compressive forces. One satisfactory conductive adhesive may be prepared by stirring 80 grams of silver flake (Metals Disintegrating Corporation MD 750, for example) into 20 grams of Shell Chemical Corporation Epon 815 epoxy resin, and using as a catalyst for the resin 2 grams triethylene tetramine (e.g., 2 grams "TETA" marketed by Union Carbide Corporation).

Following curing or hardening of the conductive adhesive 24 the unitary mass comprising the adhesively-bonded varistors 22 has soldered to end-most faces thereof respective terminal devices including wires or pigtails 18 and 18a (FIGURE 2), the terminal devices preferably including termination shims 26, 26 formed of metal which are conductively united with respective films 22s at the stack ends and to which the wires are soldered as indicated. The thus-equipped unitary assembly of varistors is closely jacketed by an insulation cover 28 (FIGURE 2) whereby the unit may be inserted into the cylindrical shell 12 and potted therein with potting compound 14p. An insulative disc 14d serves with nonconductive potting compound 14p to provide the end closure 14 which effectively seals the end of the shell against ingress of foreign material and concurrently maintains the active components of the device in place. As is made evident in FIGURE 2, the terminal wire 18 extends through an aperture in disc 14d.

At its opposite end the unitary stack of varistors is connected via the conductor (wire or pigtail 18a) to a low-voltage compensation device including in this exemplary device a pair of etched-circuit terminal boards 30, 32 of disc-like form and compensating network means 34 therebetween which network comprises diode devices. The compensating network may be of divers sorts and per se is not of the present invention. Following connection of pigtail 18a to the compensating network, nonconductive potting compound 14p' poured into the housing 12 over the unitary stack of varistors 22 and the compensating network with attached terminal boards is pressed into the housing. Potting of the entire structure in the housing is then completed in any suitable fashion, as by addition of nonconductive compound and preferably using vacuum for removal of entrapped gas. The housing is completed by emplacement of end cap 14d' as indicated in FIGURE 2.

As will now be evident, the unitary structure comprising the stack of adhesively-bonded resistors is securely fixed in place in housing shell 12, and is such that change of inter-resistor connection resistance due to mechanical movement cannot occur. The structure is sealed against ingress of foreign material, and is protected from mechanical displacements or injuries. Thus the aforementioned objects of the invention have been attained. In the light of the disclosure, changes within the true spirit and scope of the invention will be suggested to others, and hence it is desired that the invention be restricted only as required by the appended claims.

We claim:

1. A nonlinear electrical resistance device comprising: a series of electrical resistors each comprising a disc-like structure composed principally of silicon carbide crystals and a binder, each of the series of resistors bearing a conductive metal coating on at least a major portion of a face thereof, said resistors being stacked in face-to-face relationship in a generally cylindrical array;

a series of thin masses of highly conductive hardened adhesive, each of said masses being disposed between the next-adjacent faces of a respective pair of said resistors and serving to electrically interconnect the respective pair of resistors and the masses of adhesive serving to firmly mechanically bond the series of resistors into a rigid unitary structure; and end terminal devices arranged at respective ends of said unitary structure to provide electrical connection thereto.

2. A resistance device according to claim 1, in which said end terminal devices each comprise a conductive disc adhesively secured to a respective end of said series of resistors, and conductor means each fusion-united to a respective conductive disc.

3. An electrical resistance device comprising: first means, including a series of resistive disc-like devices each comprising essentially a compacted mass of polycrystalline semiconductive material and a binder, said disc-like devices being arranged in a face-to-face stack arrangement;

second means, including between opposed faces of said disc-like devices respective masses of conductive adhesive serving concurrently to effect stable electrical interconnections between the said disc-like devices and to effect stable mechanical bonds whereby the said disc-like devices are bonded into a rigid unitary electrical device; and

third means, comprising electrical terminal means electrically connected to respective end-most faces of said stack of said disc-like devices, whereby the said disc-like devices are electrically connected in series relationship and whereby the inter-disc electrical resistances of said stack of said disc-like devices remain stable incident to said device being subjected to severe vibration.

4. A resistance device according to claim 3, in which said polycrystalline semiconductive material is at least principally silicon carbide.

5. An electrical resistive device comprising:

first means, including a stack of resistive semiconductive polycrystalline elements of disc-like form the internal face-to-face electrical resistance of which resistive elements varies nonlinearly with variation of applied potential, said resistive elements being arranged generally in face-to-face contact;

second means, including a series of masses of conductive metal-containing polymer adhesive each of said masses being disposed between and in electrical contact with the contacting faces of a respective pair of said resistive elements and serving to improve the conductivity of the electrical path therebetween and further serving to adhesively bind the respective pair of resistive elements together, whereby the said stack

of resistive elements is firmly united into a rigid unitary structure with the resistive elements in electrical series relationship;
and third means, including means housing said resistive elements and providing electrical terminal connections thereto.

6. A resistive device according to claim 5, including fourth means, said fourth means including electrical compensating circuit means disposed in said housing and connected to at least one of said resistive elements.

7. An exponential resistive device characterized by an exponentially varying current flow in response to linearly varying applied potential, said device comprising:

first means, including a plurality of disc-shaped resistive members each composed essentially of a compacted mass of selected grains of crystalline silicon carbide and means binding the grains into a coherent disc-shaped mass, said members being arranged in a stack with next adjacent members in face-to-face contact;

second means, including a plurality of masses of highly conductive adhesive each disposed between the contacting faces of a respective pair of said members and serving to adhesively bind the said members into a rigid unitary mass and to improve and stabilize the

face-to-face conductivity between the respective pair of members;
third means, including generally cylindrical housing means including insulation means, serving to enclose and insulate said first and second means; and fourth means, including electrical terminal means extending from respective ends of said housing means, effective to provide electrical connections to the end-most ones of said stack of resistive members.
